(57) **CLAIM**

We claim the ornamental design for a child seat protector, as shown and described.

DESCRIPTION

FIG. 1 is a top perspective view of our design;

FIG. 2 is a plan view thereof;

FIG. 3 is a front view thereof;

FIG. 4 is a rear view thereof;

FIG. 5 is a left side view thereof a right side view being a mirror image of the view shown;

FIG. 6 is a sectional view taken along Line 6-6 of FIG. 2; and,

FIG. 7 is a sectional view taken along Line 7-7 of FIG. 2. The bottom of the child seat protector is unadorned and forms no portion of the claimed design.

The broken lines shown illustrate portions of the child seat protector and form no part of the claimed design.

1 Claim, 4 Drawing Sheets
